INVENTOR

Frank E. Barr
Dr. McNeil Grant & Co.

United States Patent Office.

FRANK E. BARR, OF ALBION, ASSIGNOR TO HIMSELF AND JULIUS J. BARR, OF ELBA, NEW YORK.

Letters Patent No. 90,915, dated June 8, 1869.

IMPROVEMENT IN THREE-HORSE EQUALIZERS.

The Schedule referred to in these Letters Patent and making part of the same.

To all whom it may concern:

Be it known that I, FRANK E. BARR, of Albion, in the county of Orleans, and State of New York, have invented a new and useful Three-Horse Equalizer; and I do hereby declare that the following is a full and exact description thereof, reference being had to the accompanying drawings, and to the letters of reference marked thereon, in which—

Figure 1 represents the equalizer as attached to the double-tree, and

Figure 2 represents the device by itself.

Similar letters of reference indicate corresponding parts.

My invention relates to a device for equalizing the draught of three horses, when hitched to the same load, and consists in attaching to the centre of the double-tree a grooved pulley, and to the load a similar pulley, and running a chain, extending from the centre whiffletree, over the said pulleys, in such a manner that the draught of the centre horse will be exactly the same as that of each of the side horses.

In the accompanying drawings—

A represents a grooved pulley, provided with the bands *a*, extending across its centre on both sides, and forming its bearings.

The ends of these bands are connected by the guard *c*, which extends half way around the circumference of the pulley.

The pinion of the pulley is clasped by the clevis *d*, by means of which the pulley is attached to the clevis

e, in the centre of the double-tree B, to the ends of which are attached the whiffletrees C C.

D is a grooved pulley, made exactly like the pulley A, and provided with similar cross-bands and guard.

g is a three-pronged clevis, the double-pronged end of which clasps the ends of the pinion of the pulley D.

The clevis *g* is attached to the load at the point marked *x*.

To the single end of this clevis is attached the chain H, which extends from thence back, up and around the pulley A, under the guard *c*, which holds it in the groove of the pulley, and from thence back, up and around the pulley D, under its guard, and from thence on to the clevis *h*, in the centre of the middle whiffletree C, to which it is attached.

By this arrangement, each of the three horses attached to the whiffletrees C, C, and C', receive, respectively, exactly one-third of the draught.

What I claim as my invention, and desire to secure by Letters Patent, is—

A three-horse equalizer, composed of the grooved pulleys A and D, with their bands *a* and guards *c*, the chain H, and clevises *d*, *e*, *g*, and *h*, together with the double-trees C, C, and C', combined and arranged in the manner shown, and for the purposes herein set forth and described.

FRANK E. BARR.
